IRONING MACHINE

Paul E. Frantz, Euclid, Ohio, assignor to The Apex Electrical Manufacturing Company, Cleveland, Ohio, a corporation of Ohio

Application February 5, 1941, Serial No. 377,543

5 Claims. (Cl. 74—290)

This invention relates to an ironing machine and more particularly to the gearing and control for the gearing of a domestic ironing machine.

It is among the objects of my invention to provide an ironing machine with a driven roll shaft adapted to be connected to and rotate with a driving member through a planetary speed reducing unit carried by said shaft.

It is a further object of my invention to provide an ironer having a driven roll shaft, a driving member rotatable on said shaft, and speed-reducing means interposed between said driving member and the shaft whereby the shaft may be rotated at the same speed or a lower speed than the driving member.

It is a further object of my invention to provide an ironer according to the preceding object in which the speed-reducing device includes a planetary gear drive concentric with and supported by the driven shaft.

It is a further object of my invention to provide an ironer according to the preceding objects in which the connection between the driving member and the driven shaft includes a spring clutch adapted to transmit the drive from the driving member to the driven shaft throughout all speeds of the driven shaft.

It is a further object of my invention to provide an ironer according to the preceding objects in which the speed-reducing mechanism is utilized in the chain of drive between the driving member and the driven shaft throughout all speeds of the driven shafts.

Further objects and advantages relating to simplicity in construction, efficiency in operation and low cost of manufacture and assembly will appear from the following description and the appended drawings, wherein:

Figure 1 is a perspective view with parts broken away of an ironer constructed according to my invention;

Figure 2 is an elevation with parts in section of the ironing machine gearing;

Figure 3 is an end view with parts broken away showing the control means for the two-speed drive;

Figure 4 is an elevation with parts in section showing the speed control in a normal speed position;

Figure 5 is an elevation similar to Figure 4 showing the parts in a neutral or "off" position;

Figure 6 is an expanded view of elements included in the reduced speed planetary gearing mechanism;

Figure 7 is a view showing the gear carrier of the reduced speed mechanism with the sun gear and planet gear in phantom outline;

Figure 8 is an end view of a ring element included in the reduced speed mechanism;

Figure 9 is an end view of a plate element employed in the reduced speed mechanism;

Figure 10 is a view of a clutch element employed in a reduced speed mechanism;

Figure 11 is an end view showing parts of the reduced speed mechanism as assembled;

Figure 12 is an end view similar to Figure 11 showing the sliding clutch and clutch control members for the reduced speed mechanism.

Figure 13 is a sectional view of a modified form of reduced speed mechanism;

Figure 14 is an elevation of the modification shown in Figure 13; and

Figure 15 is a sectional view of a modified form of reduced-speed mechanism.

My invention relates generally to that type of domestic ironer comprising a heated shoe and a rotating roll with means to effect relative movement between the shoe and the roll so that garments may be ironed therebetween.

The wide current use of domestic ironing machines has brought about a recognition of the need for a driving mechanism for the ironer roll which will permit the operation of the roll at more than one speed of rotation. This need arises from the fact that the moisture content and the thickness of garments vary through a relatively wide range. For instance, the hem of a garment may present two or three thicknesses

of fabric as compared to a single thickness of fabric in the main body of the garment and it is necessary for satisfactory ironing results to remove the moisture from the hem as well as the main body of the garment. Thus it is desirable to run the thickened portions of a garment or heavy garments containing considerable moisture through the ironer at a lower speed than that employed for ironing thinner fabrics or fabrics low in moisture content.

Among the expedients employed to provide a two-speed roll drive is the provision of a two-speed electric motor. The expense and inefficient operation of this expedient led to numerous attempts to provide sliding gear transmissions having two speeds or planetary gear sets providing two or more speeds. The provision of change-speed gearing to provide two roll speeds has prior to my invention necessitated a redesign of the gear case and gearing to accommodate the added mechanism. According to my

invention the two-speed gearing is so designed, proportioned and so arranged as to cooperate with the balance of the ironing gearing mechanism that the same may be incorporated in a gear case proportioned to house a conventional, single-speed driving mechanism.

Among the advantages flowing from the arrangement I have provided, is, that it is unnecessary for the ironer manufacturer to provide two separate and distinct ironer assemblies, one for a single or direct speed drive and another for the higher-priced range including a two speed drive. This advantage will become more apparent by reference to the single-speed ironer disclosed in the patent to Racklyeft 2,087,447 and the application of my invention to an ironer of the type disclosed in said patent.

Generally speaking, I have obtained the objects above referred to and the advantages associated therewith by the provision of a driving member freely rotatable about a driven shaft, a planet gear carrier secured to said shaft and a coil spring clutch arranged to transmit the drive from the driving member through the planetary gear carrier and thence to the driven shaft.

Referring to the drawings, 1 indicates a gear case or housing which is adapted to be mounted at one end of a stand or table, a pair of bosses 2 and 3 project axially of the gear case and support shafts 4 and 5 designed to bring about the relative movement between a heated shoe and the roll and to rotate the roll with respect to the shoe. The shaft 4 is designed to rock an eccentric within the roll to move the roll toward and away from the shoe. The shaft 5 provided with pinion 5a drives a ring gear carried by the roll when the roll is moved into engagement with the shoe. Reference is made to the application of J. W. Racklyeft, Serial No. 111,695, filed November 19, 1936, for a more complete disclosure of the roll mounting and drive therefor. The specific mounting for the roll with respect to the shoe and the manner in which the roll is rotated is the invention of said Racklyeft and since the said construction forms no essential part of my invention, further description of that part of the ironer is omitted. Reference is made to said patented Racklyeft construction as providing the environment of my invention.

The power for the operation of the ironer gearing is introduced through the medium of a belt 7 engageable by a motor pulley, not shown, to rotate the pulley 8 in the direction indicated by the arrow 9. The belt pulley is secured to the shaft 10 supported in opposed bearing bosses 11 and 12 in the gear case 1. The shaft 10 is provided with a worm 13, intermediate its supported ends, which is adapted to mesh with a driving worm gear 14 mounted at right angles thereto. A support and bearing sleeve 15 are carried by the boss 3 and project inwardly of the gear case to afford a mounting for the gearing mechanism and a bearing support for the driven roll shaft 5. The driving worm gear 14 is freely rotatable on the sleeve 15 and is adapted to turn a sleeve 16 at the left side thereof (see Fig. 2).

A roll shifting eccentric 17 is mounted on the sleeve 15 and is provided with a hub portion coaxially arranged with the member 16 so that a spring clutch 18 which surrounds said hub and member 16 may transmit the rotating drive from 16 to the eccentric 17. The movement of the eccentric 17 is transmitted through the eccentric strap 19 to a crank 20 secured to the inner end 75

of shaft 4. The engagement and disengagement of the spring clutch so as to effect eccentric movement is controlled by a manually-operated shaft 21 having an inturned end 22 adapted to engage spaced ears 23 on a clutch plate 24.

It will be understood that the construction is such that the direction of rotation of the driving gear 14 tends to wrap the spring clutch member 18 tightly about the hub on member 17 and the sleeve 16 and that such wrapping action may be interrupted by moving the end 22 of the shaft 21 into the path of the ears 23. The ears 23 are preferably spaced 180° from each other so that a half revolution of the eccentric 17 is obtained each time the shaft 21 rocks the end 22 out of the path of said ears. A spring on the shaft 21 normally returns the end 22 to an engaging position with ears 23 after each manual operation of the shaft 21. The shaft 21 may be operated by the hand control 25 or by the knee control 26 so that the eccentric 17 moves 180° upon each actuation and thus rocks the shaft 4 to move the roll toward or away from the heated shoe upon each actuation.

25 The eccentric 17 is provided with an integrally formed braking segment 27 which is adapted to be moved into the path of a peripheral brake shoe 28 each time the eccentric is rocked to a position where the roll is in engagement with the ironing shoe. A coil spring 29 urges the shoe 28 against the segment 27 at a time when the shoe is against the roll and the advantage of this arrangement is that the roll recedes gradually from its engaged position with the shoe when the clutch 18 is released.

It will be appreciated by those skilled in this art that considerable pressure is developed by the engagement between the shoe and the roll and that the resilient mounting of the shoe would tend to accelerate the movement of the roll away from the shoe in the absence of a retarding force such as provided by the brake shoe and segment engagement 28-27.

The driving worm gear 14 is provided with an integrally-formed hub 30 which has fixed thereto a sleeve 31 (see Fig. 2). A clutch plate 32 is mounted for free rotation on the sleeve 31 with the radial expance of the plate supported by bearing against the side of the driving gear 14. A coil spring 33 surrounds the sleeve 31 and an upturned end 34 of the spring clutch is disposed between spaced lugs 35a and 36a formed on the face of the clutch plate 32. The axial extent of the spring clutch member 33 exceeds the length of the sleeve 31 so as to embrace the hub 35 of a driving gear 36. The end 38 of the coil spring clutch adjacent the gear 36 projects outwardly into the path of the pin 39 projecting axially from the radial wall of the gear 36. The direction of rotation of the driving gear 14 is in the direction of the arrow 40 and the direction of the spiral in the spring clutch 33 is such that the coil spring tends to be wrapped tightly about the coaxial portions of the sleeve 31 and hub 35 so as to transmit the rotating movement of the driving gear 14 to the driving gear 36.

The normal engaged position of the spring clutch 33 is interrupted by moving the end portion 44 of shaft 45 into the path of ears 46 projecting from the radial face of the clutch plate 32. The disengaging clutch action above described is effected by manually moving the control lever 47 secured to a portion of the shaft 45 projecting exteriorly of the gear case 1.

All of the rotating movement transmitted to

the shaft 5 from the driving gear 14 comes through the gear carrier element 48 secured by threaded engagement to the shaft 5. It will be understood by means hereinafter described that the gear carrier 48 may be engaged to rotate in unison with the driving gear 14 or engaged to rotate at a lower speed than the driving gear 14. The means to accomplish said reduced speed drive comprises a planetary gearing arrangement concentric with and supported by the shaft 5. More specifically the member 36 is provided with internal gear teeth 58 adapted to mesh with the teeth of a planetary gear 51 rotatably mounted on the gear carrier 48. The planetary gear 51 is also in mesh with the teeth of a sun gear 52 which is rotatably mounted on a reduced end portion of the shaft 5. It will be appreciated by those skilled in the art that whenever the sun gear 52 is restrained from rotation upon its axis, the planetary gear 51 will be constrained to rotate on its own axis through its orbit. Thus the planet gear 51 will "track around" the sun gear 52 and move the gear carrier about its axis at a speed less than the speed of rotation of the driving gear 36. It will also be understood that when the sun gear is free for rotation upon its own axis and the planetary gear 51 is clutched thereto, the gear carrier, sun gear, planet gear and driving gear 36 will all rotate as a unit so as to rotate the shaft 5 at the same speed as the driving gear 14.

In the preferred form of my invention a ring-like element 60 is mounted for free rotation upon an annular shoulder 61 of a clutch plate member 62. A plurality of spaced pins 63 project axially from the plate 62 and are received in correspondingly spaced holes 64 in the sun gear 52. The ring element 60 is notched as at 65 to embrace the head of a screw 66 anchored to the gear carrier coaxial with the planetary gear 51. The ring element 60 is also provided with spaced lugs 67 adapted to cooperate with the inturned end 68 of a clutch member 69. The arrangement thus described provides that when the clutch member 69 is moved transversely of the axis of the shaft 5, as provided by slot 70 in the member 69, the ring 60 and the gear carrier 48 are free to rotate about the axis of shaft 5. When the gear carrier 48 and ring 60 are thus freed for rotation and the sun gear restrained through the medium of pins 63 and member 62, the planetary gear will be constrained to track around the sun gear to effect a reduced speed or low speed drive to the shaft 5. A clutch member 69 is mounted for sliding movement transverse of the shaft 5 by the guide segments 71 and 72 spot-welded or otherwise fixed to the member 62. A bearing sleeve 70a extends through the member 62 and the slot 70 in element 69 to mount said member and element on the shaft 5. A coiled spring 73 anchored at one end as at 74 to plate 72 and at the other end at 75 on the clutch member 69, normally urges the clutch member 69 transversely of the shaft 5 to the position shown in Figure 12, wherein further movement of the member 69 is prevented by a stop 76 formed on the member 71. The entire two speed assembly is retained in position on shaft 5 by the washer and clip 6a and 6b respectively.

With the parts in the position shown in Fig. 12, it will be observed that the tail piece 68 of the clutch member 69 is in the path of the lugs 67 so that the sun gear 52, the ring member 60 and the gear carrier 48 rotate as a unit at the

same speed as the driving members 14 and 36, and thus the ironer roll is rotated at a normal or full speed drive. When, however, the clutch member 69 is moved transversely in opposition to spring 73, as shown in Fig. 3, the tail piece 68 on the member 69 is moved out of the path of the lugs 67 on ring 60 so that the gear carrier is free to rotate, the planetary gear will move through its orbit about the sun gear and effect a reduced or low speed drive to the shaft 5.

According to my invention, the control shaft 45, arranged to establish a drive from the driving gear 14 through the spring clutch 33 to the driving gear 36, also controls the speed which is to be maintained through the planetary gearing. The arrangement is such that the control of the spring clutch 33, the establishment of normal or direct speed drive, and the establishment of reduced or low-speed drive, occur in sequence. The construction provides that the first portion of the movement of the control shaft 45 effects engagement of the spring clutch 33 and the second portion of the shaft movement in the same direction establishes a reduced speed drive. The result is an interlock effect which precludes the establishment of a reduced speed drive position without first effecting an engagement of the coiled spring clutch through which the drive is maintained.

The above-described functions are preferably obtained by the control mechanism illustrated in Figs. 2 to 5, inclusive.

Referring to Fig. 3, the gear case 1 is provided with a web section 80 upon which is pivoted a lever comprising two interconnected sections 81 and 82. The two lever parts are pivoted to the web 80 of the gear case by means of stud 83 and the free end of the lever part 81 is provided with a shoulder 84 and a tail piece 85 which are adapted to cooperate with the clutch element 69 and the portion 76 of a guide plate 71 on member 62.

It will be observed by reference to Fig. 3 that when the two-speed clutch assembly is rotated in the direction of the arrow 86, and the lever 81 is moved in a clockwise direction into the path of the parts 76 and 69a, the clutch member 69 will be moved to the position shown in Fig. 3 and the tail piece 76 will be restrained in the opening between lever parts 84 and 85. The effect of this movement will be to restrain the sun gear from rotation upon its axis and free the planet carrier for rotation in reduced speed drive as heretofore described. To insure that the lever part 81 will be moved into the position shown in Fig. 3 with an impositive, soft, engaging action, it is moved to said position through the medium of the spring 87 carried by studs 88 and 89 integral with lever parts 82 and 81, respectively. This arrangement provides that the lever part 82 may be positively moved to the position shown in Fig. 3 and that lever part 81 will be impositively moved and free to rock about the pivot 83 in response to a camming action by the part 76 as it traverses the portion 84 of the lever 81.

The composite lever unit 81-82 is normally urged in a counter-clockwise direction by the spring 90a anchored at one end on the web 80 and at the other end on the lever part 81. A lug 91 limits the movement of the lever part 82 in a counter-clockwise direction with respect to the lever part 81 in response to the urging of the coil spring 87. The free end of the lever part 82, such as indicated at 92, is embraced by side walls of a slot formed in the outer end of the pivoted arm 83. The other end of the arm 82 is pivoted for

free rocking movement on the control shaft 21, and the intermediate portion of the arm 93 is shaped to provide a cam 94 adapted to cooperate with a cam 95 carried by the control shaft 45.

With the control shaft 45 in a neutral or "off" position as shown in Fig. 5, the portion 44 of the shaft is in engagement with the ears 46 on the clutch plate so that the spring clutch 33 is disengaged. When, however, the control shaft is turned in a counter-clockwise direction to the position shown in Fig. 4, the cam 95 engages the cam 94 on the lever 93 so as to free the end 44 of the shaft 45 from the clutch ears 46. This effects a spring clutch engagement so that the full speed or direct drive is established to the roll shaft 5. Thereafter, in the event a low-speed drive is desired, the control shaft 45 may be rocked still further in a counter-clockwise direction so that the cam 95 cooperates with the cam 94 on the lever 93 to rock the composite lever unit 81-82 to the position shown in Fig. 3. The slotted free end of the arm 93 is preferably provided with an adjusting screw and lock nut assembly 97-98 to provide an accurate positioning of the composite lever assembly 81-82.

Although in the preferred form of my invention I have employed a clutching device for the planetary gear reduction which includes a clutch member sliding transversely of the driven shaft, I am aware that other forms of clutching devices may be employed. In Figs. 13 and 14 I have illustrated a clutch arrangement for the planetary, two-speed mechanism which provides for automatic engagement. In this form of my invention, the driven shaft 5 is provided with a gear carrier 100 encompassed by a driving gear 101 constructed and arranged substantially as in the preferred form. The gear carrier is provided with a planetary gear 102 mounted thereon by cap screw and washer 103-104. A sun gear 105 is mounted for rotation upon the end of the driven shaft 5 and a uni-directional clutch comprising rollers 106-107 is arranged between the sun gear 105 and the shaft 5. The roller clutch and sun gear are retained in operative position on the shaft 5 by a cap screw and disc 108-109.

Referring to Fig. 14, it will be observed that when the driving gear 101 is rotated in the direction of arrow 110, it will tend to turn the planetary gear 102 on its axis in a clockwise direction and this tendency will in turn tend to rotate the sun gear in a counter-clockwise direction, as indicated by arrow 111.

The roller clutch assembly includes coil springs 112 and 113 which act to move the rollers into the reduced or tapered opening between the roller clutch housing wall and the driven shaft 5 and thus the sun gear becomes automatically clutched to the shaft 5 and further rotation of the sun gear with respect to the shaft is prevented.

As soon as the sun gear becomes clutched to the shaft, as above described, further rotation of the planet gear upon its axis is prevented and thus the gear carrier, sun gear and planet rotate as a unit about the axis of the shaft 5 so as to effect a direct or full-speed drive of the ironer. The sun gear is proportioned axially so that the teeth thereof project axially beyond the vertical face of the planetary gear assembly and when it is desired to establish a low speed or reduced speed drive, a stop member indicated at 115 is projected into the path of the sun gear 105. The restraint thus imposed on the sun gear frees the roller clutch from clutching engagement between the sun gear and the driven shaft 5. With the

sun gear restrained against movement on its axis and the driven shaft 5 freed of the roller clutch, the gear carrier 100 is free to rotate and the planet gear "tracks around" the sun gear in response to the drive imparted to the planet gear through the driving gear 101.

The stop member 115 may be fixed to a rocking lever corresponding to the lever 81 in the preferred form of my invention and thus the single lever 47 may control the neutral, full speed and second speed drive through the ironer.

The modification shown in Fig. 15 corresponds generally in operation and results to that shown in Figs. 13 and 14. In the form of Fig. 15, however, a uni-directional clutch comprising a coil spring clutch element 117 is arranged to automatically clutch the sun gear 125 to the driven shaft 5. The sun gear is provided with a recess to receive the inturned end 116 of the coil spring clutch and the other end of the coil spring clutch terminates in a bent end 118 received within an aperture in a clutch plate 122. The plate 122 is provided on its periphery with lugs 119 adapted to engage a stop member constructed to move into the path of the lugs. The stop member may be of the form such as illustrated at 115 in Fig. 14. The clutch assembly in this modification may be retained in place on the shaft 5 by a washer and cap screw 120-121.

In the modifications shown in Figs. 12, 14 and 15, it will be observed that the engagement and disengagement effected by the uni-directional clutch may take place at any phase during the rotating movement of the sun gear, as distinguished from the preferred form of the invention illustrated in Fig. 1, wherein there is but one point during each revolution of the shaft 5 where the clutch will be operated. It will be observed that the stop member 115 is constructed so as to prevent rotation of the sun gear in either direction whenever the stop is moved to disengaging position and thus variations in load imposed will not adversely effect the clutch operation.

All forms of planetary gear clutching devices I have shown provide certain advantages, the preferred form being characterized by the fact that it comprises a number of simple, stamped metal parts and requires no internal machining of the sun gear to accommodate a roller clutch. The modified forms of Figs. 13 to 15 are characterized by being automatic in their clutching action and comprising relatively fewer parts than that of the preferred form.

Although I have shown and described three forms of my invention in considerable detail, it will be appreciated by those skilled in the art that numerous modifications may be made therein without departing from the scope of the invention as defined in the following claims.

Having thus described my invention, what I claim is:

1. An ironer mechanism comprising a gear case, a boss formed in one side of said gear case, a driven shaft rotatably supported by said boss, a driving gear rotatably mounted on said driven shaft, a hub on said driving gear, a second driving gear rotatably mounted on said shaft, a hub on said second driving gear coaxial with the hub on the first driving gear, a coil spring clutch encompassing said two hub portions, a planetary gear carrier fixed to said driven shaft adjacent said second driving gear, a sun gear on said driven shaft adjacent said gear carrier, a planetary gear engaging said sun gear and

said second driving gear, means to prevent movement of the gear carrier with respect to said sun gear to establish a direct drive between said second driving gear and said shaft and means to render said first-named means inoperative and restrain said sun gear whereby said shaft is rotated at a reduced speed with respect to said second driving gear.

2. An ironer comprising a gear case, a boss formed in one side of said gear case, a driven shaft rotatably mounted in said boss having one end projecting from the gear case and the other end extending into the gear case toward the wall thereof opposite the boss, a driving gear mounted on said shaft for free rotation with respect thereto, a planet gear carrier fixed to said shaft at said other end, a second driving gear supported for rotation with respect to the axis of said shaft by said gear carrier, a coil spring clutch interposed between said two driving gears, a sun gear mounted for free rotation in one direction on said shaft, a planet gear mounted on said gear carrier in mesh with said sun gear and said second driving gear and means including a uni-directional clutch to engage said gear carrier with said second driving gear so as to rotate therewith and means to restrain said sun gear against rotation whereby said gear carrier rotates at a reduced speed with respect to said second driving gear.

3. An ironing machine comprising a gear case, a bearing boss formed in one side of said gear case, a shaft supported in said bearing boss and projecting toward the other side of the gear case, an opening formed in said gear case opposite said bearing boss to provide for the assembly of gearing on said shaft, a driving gear mounted for rotation near the central portion of said shaft, a hub on said driving gear projecting toward said opening, a gear carrier fixed to said shaft at the end thereof adjacent said opening, a second driving gear surrounding said gear carrier, a coiled spring clutch encompassing said hub and a part of said second driving gear, a sun gear rotatably mounted on said shaft, a planetary gear in mesh with said sun gear and said second driving gear, means to rotate said gear carrier in unison with said second driving gear or at a reduced speed with respect thereto comprising a plate anchored to said sun gear, a clutch member mounted on said plate for slipp-

ing movement transverse to the axis of said shaft, means on said plate movable into the orbit of said planetary gear to prevent rotating movement of said gear carrier with respect to said sun gear, to establish a direct speed drive and means carried by said gear case to move said clutch means out of said orbit path and restrain said plate to establish a reduced speed drive through said planetary gearing.

4. An ironing machine comprising a gear case, a roll driving shaft supported in said gear case, a driving gear mounted for rotation on said shaft, a gear carrier fixed to said shaft, a second driving gear surrounding said gear carrier, a helicoid spring clutch engaging said two driving gears, a sun gear rotatably mounted on said shaft, a planetary gear on said gear carrier in mesh with said sun gear and said second driving gear, means to rotate said gear carrier in unison with said second driving gear or at a reduced speed with respect thereto, comprising a plate anchored to said sun gear, a clutch member mounted on said plate for sliding movement transverse to the axis of said shaft, means on said plate movable into the orbit of said planetary gear to prevent rotating movement of said gear carrier with respect to said sun gear, to establish a direct speed drive and means carried by said gear case to move said clutch means out of said orbit and restrain said plate to establish a reduced speed drive through said planetary gearing.

5. An ironing machine comprising a support, a roll driving shaft rotatably mounted in said support, a driving gear mounted for free rotation on said roll driving shaft, a gear carrier fixed to said shaft, a spring clutch operatively arranged in the chain of drive between said driving gear and said gear carrier, a sun gear mounted on said shaft adjacent said gear carrier, a planetary gear in mesh with said sun gear, a second driving gear encompassing said gear carrier, planet gear and sun gear, a spring clutch interposed between said shaft and said sun gear, whereby rotation of said second driving gear operates said last-named spring clutch to engage said sun gear with said shaft and means to disengage said last-named spring clutch to effect a reduced speed drive through said gearing.

PAUL E. FRANTZ.
